W.M. Miller,

UNITED STATES PATENT OFFICE.

WILLIAM M. MILLER, OF AZUSA, CALIFORNIA.

CONDIMENT-HOLDER.

1,217,045.

Specification of Letters Patent. Patented Feb. 20, 1917.

Application filed November 2, 1915. Serial No. 59,254.

To all whom it may concern:

Be it known that I, WILLIAM M. MILLER, a citizen of the United States, residing at Azusa, in the county of Los Angeles and State of California, have invented new and useful Improvements in Condiment-Holders, of which the following is a specification.

This invention relates to condiment holders, and it has for its object to produce a simple and improved condiment holder having compartments for containing two different condiments, such as salt and pepper, a sifting top communicating with both compartments, and means whereby the one compartment is obstructed, while the other is left open to permit its contents to be sifted out.

A further object of the invention is to produce a device of the class described having a stationary sifting top and a slidable obstructing member movable thereon.

A further object of the invention is to simplify and improve the manner of mounting the stationary sifting top and the obstructing slide movable thereon.

With these and other ends in view which will readily appear as the nature of the invention is better understood, the same consists in the improved construction and novel arrangement and combination of parts which will be hereinafter fully described and particularly pointed out in the claim.

In the accompanying drawing has been illustrated a simple and preferred form of the invention, it being, however, understood that no limitation is necessarily made to the precise structural details therein exhibited, but that changes, alterations and modifications within the scope of the claim may be resorted to when desired.

In the drawing,

Figure 1 is a perspective view of a condiment holder constructed in accordance with the invention.

Fig. 2 is a side view of the same.

Fig. 3 is a vertical sectional view taken on the line 3—3 in Fig. 2.

Fig. 4 is a vertical sectional view taken on the line 4—4 in Fig. 3.

Corresponding parts in the several figures are denoted by like characters of reference.

The body of the improved condiment holder, which may be constructed of china, earthenware, glass or vitreous material of any kind, has in the drawing been shown as being of rectangular cross section, tapering

from the bottom in an upward direction, said body being in the nature of a box or container 15 having two compartments 16, 17 which are separated by a vertical partition 18. The side walls of the box are provided near the upper end thereof with grooves 19. The stationary sifting top 20 is made preferably of sheet metal, and it is provided with downturned flanges 21 at the side edges thereof, said flanges being inset into the grooves 19 of the box or container. The ends of the sifting top are also provided with downturned flanges 22 that abut on the end walls of the box or container, thereby preventing the sifting top from being displaced by sliding it endwise from the box. The sifting top is provided with two sets or series of perforations 23, 24 communicating, respectively, with the compartments 16, 17, 75 said apertures being of proper sizes to permit the sifting therethrough of the contents of said compartments, such as salt and pepper, although obviously the container may be used for condiments of any kind. The bottom of the container is provided with openings 25, 26 communicating with the respective compartments 16, 17 for the purpose of filling the latter, said openings being obstructed by stoppers 27 of cork or other suitable material.

It will be observed that by insetting the side flanges 21 of the stationary sifting cover 20 into the grooves 19, the latter is given a dovetail form, clearly seen in Fig. 3 of the drawings, thereby enabling an obstructing member 28 to be slidably mounted on said sifting cover, said obstructing member being provided with downturned flanges 29 engaging the dovetail flange 21, and said obstructing member being also provided at the ends thereof with upturned flanges 30 affording finger holds, whereby the slide may be readily moved from one end of the sifting top to the other, thereby obstructing one set of 100 perforations while the other set is left uncovered.

It is obvious that when the compartments of the device are filled with condiments and the perforations communicating with one of said compartments are obstructed, the contents of the other compartment may be readily sifted out. By simply pushing the obstructing member 28 from one end of the sifting top to the other, the contents of the 110 other compartment will be made available. By adjusting the obstructing member 28 in

an intermediate position, the contents may be simultaneously sifted from the two compartments, the relative proportions being regulated by the position of the obstructing member.

Having thus described the invention, what is claimed as new, is:—

10 A condiment holder comprising a receptacle of substantially rectangular cross section, said receptacle having a partition extending from the top to the bottom thereof, and said receptacle being provided with longitudinal grooves near the upper end thereof, in combination with a sifting top having

side flanges bent into the longitudinal 15 grooves to produce a dovetail construction, and an obstructing member having flanges slidably engaging the dovetail flanges of the sifting top, whereby said obstructing member may be adjusted to entirely obstruct one 20 compartment and also to partly obstruct the two compartments of the receptacle.

In testimony whereof I affix my signature in presence of two witnesses.

WILLIAM M. MILLER.
